UNITED STATES PATENT OFFICE

164,986

BELT BUCKLE OR THE LIKE

Luca Fantaccione, Attleboro, Mass., assignor to Leavens Manufacturing Co., Inc., Attleboro,
Mass., a corporation of Massachusetts

Application May 16, 1951, Serial No. 15,199

Term of patent 7 years

(Cl. D17—1)

To all whom it may concern:

Be it known that I, Luca Fantaccione, a citizen of the United States, residing at Attleboro, in the county of Bristol and State of Massachusetts, have invented a new, original, and ornamental Design for a Belt Buckle or the like, of which the following is a specification, reference being had to the accompanying drawing, forming a part hereof wherein,

Fig. 1 is a top edge view of a belt buckle embodying my new design;

Fig. 2 is a front elevational view of the belt buckle; and

Fig. 3 is a rear elevational view thereof.

I claim:

The ornamental design for a belt buckle or the like, as shown.

LUCA FANTACCIONE.
